UNITED STATES PATENT OFFICE.

FREDERICK B. KOLLMERG, OF BISBEE, ARIZONA, AND MAX KRAUT, OF LOS ANGELES, CALIFORNIA, ASSIGNEES TO SOUTHWESTERN ENGINEERING COMPANY, A CORPORATION OF CALIFORNIA.

APPARATUS FOR AERATING LIQUID.

1,319,667.

Specification of Letters Patent Patented Oct. 21, 1919.

Application filed November 8, 1916. Serial No. 130,189.

To all whom it may concern:

Be it known that we, **FREDERICK B. KOLLMERG**, residing at Bisbee, in the county of Cochise, State of Arizona, and **MAX KRAUT**, residing at Los Angeles, in the county of Los Angeles, State of California, both citizens of the United States of America, have invented new and useful Improvements in Apparatus for Aerating Liquid, of which

10 the following is a specification:

This invention relates to an apparatus for aerating liquid, and is especially adaptable for aeration of pulp in mineral separation processes.

15 It is an object of this invention to provide an aeration means for producing a froth with a minimum of energy.

Heretofore mechanical agitation of pulp in flotation machines for the purpose of 20 producing a froth has been very inefficient, because of the wastage of energy in moving the pulp about without accomplishing the entraining of any great amount of air. By means of our apparatus we expose a maximum of surface of the pulp to the air, introduce the air into a passage, move the pulp over the air, thereby forming bubbles, and move the bubbles and pulp from the passage.

30 The apparatus herein described is the apparatus employed in practising our process which is described in U. S. Patent No. 1,261,556, issued to us on April 2, 1918.

In the drawing, Figure 1 is a vertical 35 transverse section through the aeration chamber of the apparatus.

Fig. 2 is a detail sectional fragment of the preferred form of aerating drum shown in Fig. 1.

40 Fig. 3 is a detail sectional view of a fragment of a modified form of aeration drum.

Fig. 4 is a vertical central longitudinal section through the aeration chamber of the apparatus.

45 Fig. 5 is a developed fragmentary diagrammatic view in section of the preferred form of aerating drum and casing.

Fig. 6 is a diagrammatic view similar to Fig. 5 of the modified form of aerating

50 drum shown in Fig. 3 and casing.

Referring more particularly to the drawing, an elongated substantially rectangular aeration chamber 1 is mounted upon a suitable supporting framework 2. Extending

along one side of the chamber 1 and substantially co-extensive therewith, is a frothing chamber or box 3, which is open at its upper side and provided with an inclined bottom 4. Communicating with the head end of the aeration chamber 1 is an entrance opening or passage 5, through which the pulp to be treated is introduced into said chamber. Leading from the bottom of the frothing chamber 3 at the opposite or tail end of the machine is a discharge pipe, 6 not shown, through which tailings are discharged.

Formed in one side of the chamber 1 adjacent the upper edge thereof and extending longitudinally thereof is an aeration chamber discharge outlet 6 from which leads a downwardly extending passage 7, which communicates at its lower end with the chamber 3 as shown.

Arranged below the lower end of passage 7 is a baffle board or flange 8 which serves to deflect the pulp discharged through said passage outwardly. Leading from the bottom of the frothing chamber 3 to the bottom of the aeration chamber 1 are spaced return openings 9 which are controlled by a sliding gate 10 having a notched lower edge to correspond with said openings 9.

Arranged in the aeration chamber 1 is the aeration element or drum 11. Said drum consists of a cylindrical wall 12 which is bolted as shown to spiders 13 fixed to a shaft 14 extending centrally through the aeration chamber and having its end suitably mounted in bearings provided at the end of said chamber. Air may freely circulate through the drum around the spider arms. The cylindrical wall 12 is provided with perforations 15 which extend therethrough and communicate with the interior of the drum. The periphery of the wall 12 is preferably roughened by arranging thereon a plurality of closely spaced longitudinally extending ruffles 16 as shown in Fig.

2. The ruffles 16 serve to entrap air therebetween and pocket or hold the same while the pulp slips thereover. In Fig. 3 the air is held by frictional contact with the surface of the drum and the pulp slips thereover.

Provided in the chamber 1 at the lower edge of the outlet opening 6 is an inwardly projecting flange 17 which serves to direct

toward said outlet opening the thin sheet of pulp centrifugally thrown from the aeration drum. Communicating with the upper end of the aeration chamber is a plurality of air supply pipes 18, passage through which is controlled by valves 19. Arranged in chamber 1 below the lower end of the air supply pipe 18 is a deflecting board 20 so arranged that the air which is supplied 10 to the chamber 1 will be introduced into said chamber and adjacent the periphery of the aeration element tangentially thereto and in a direction toward the outlet opening 6. The thin sheet of pulp thrown from 15 the aeration drum induces air from pipes 18 increasing the aeration of the pulp.

Oil supply pipes 21 are employed, communicating with the interior of the chamber, and are controlled by valves 22. A 20 casing 23 is spaced from and about the rear portion of the drum 11 as indicated in Fig. 1, thereby providing an aeration space 24 of arcuate section through which the pulp travels and in which it is aerated. The 25 casing 23 at its lower part is extended to the floor of the aeration chamber in a direction tangential to the aeration drum. This construction assists in the direction of pulp to the inlet of the aeration space. 30 In operation the aeration drum 11 is rotated at a suitable speed. The pulp level inside the aeration chamber is maintained by means of the gate 10 at such a height that the outer surface of the aeration drum 35 is slightly immersed in the pulp, the latter being slightly higher than a tangent to the lower surface of the drum. The level is maintained just sufficient to fill the entrance to the aeration space 24. A greater height is 40 not desirable as agitation and beating of the pulp will result. This is ineffective in producing aeration and results in a loss of power. Excessive beating of the pulp may also result in emulsification which is found 45 to be undesirable.

In the rotation of the drum the adhesion of the pulp to the drum causes a flow of the pulp at high velocity through the aeration space 24. This produces a high velocity 50 head and a low pressure head, the pressure head decreasing with the increase of velocity head. By imparting sufficient velocity to the pulp the pressure head may be decreased to less than atmosphere pressure, and air induced through the perforations 15. It will 55 be noted that air may readily enter the interior of the drum through the hollow drip cups at each end of the chamber 1. Air is thereby introduced into the pulp and 60 mingled therewith. Aerated pulp is thrown off the surface of the drum at the upper end of casing 23, due to the centrifugal action and encounters the apron 17, being directed thereby into the outlet opening 6; air is also 65 induced through the pipe 18 into the aerat-

ing chamber, mixing with the pulp as it is thrown from the drum.

As the pulp passes into the passage 7, it moves downwardly into the frothing chamber. The froth overflows from the top of 70 the frothing chamber carrying with it mineral, and the pulp sinks to the bottom for retreatment on return through opening 9 to the air chamber.

In mechanically actuated flotation machines especially of the horizontal type, bearings are necessary for the shaft carrying the agitators. These bearings, when below the level of the pulp, must be packed to prevent the pulp from leaking therethrough. Due 75 to the sand and other gritty material in the pulp, the bearings and shaft rapidly wear and must be repaired and replaced. Our machine is not subject to such difficulty, as the bearings for the aeration drum shaft 80 are not in contact with the pulp.

In the operation device shown herein, air is induced through perforations 15, meets the surface of the thin stream of pulp which is moved by the drum through passage 24, 90 because of adhesive and viscous action. There is a slippage of pulp relative to the drum, and the air entering the passage slips along the surface of the drum pocketing itself between riffles 16 in the preferred 95 form of drum, or being held by the frictional action of the drum surface in the modified form, shown in Fig. 3. While held thus, the pulp draws a film thereover and bubbles are formed. The pulp and bubbles 100 are then carried by the drum to the discharge exit of the passage 24 and thrown from the drum through opening 6 into the frothing chamber. This machine does not 105 depend upon agitating the pulp, as a very slow rotation of the drum will result in aeration.

In Fig. 5 the pulp passing through aeration space 24 is shown with air pocketed between the riffles 16, the relative movement 110 of the pulp and the wall 12 of the drum being indicated by arrows. The moving wall 12 carries the pocketed bubbles to the outlet of space 24 and discharges the pulp and bubbles in the form of a pulp. In Fig. 115 6 the air is drawn through perforations 15 into the space 24, being held by frictional contact with wall 12. Bubbles are thus formed and the pulp and bubbles moved through space 24 to the outlet.

What we claim is:

1. In a flotation machine, the combination of a moving wall having pockets on the surface and a relatively stationary wall spaced therefrom forming a passage, said moving wall provided with perforations for the introduction of air to said passage.

2. A machine for aerating liquid, comprising a rotatable element, a casing forming therewith a substantially unobstructed

passage, said rotatable element arranged for contact with a liquid in said passage to cause high velocity flow thereof by viscous and adhesive action thereof, and an inlet

5 to said passage for aerating liquid.

3. A machine for aerating liquid, comprising a rotatable perforated drum, a casing forming therewith a substantially unobstructed passage, said rotatable drum arranged for contact with a liquid in said passage to cause a high velocity flow thereof by viscous and adhesive action thereof, air being admitted to said passage for aerating said liquid through the perforations in

10 said drum, and an inlet and outlet to said passage for the aerated liquid.

15 4. In a flotation machine, the combination of an aeration chamber, a rotatable drum

therein, a casing spaced from and forming a partially cylindrical aeration passage, and 20 means establishing communication between the atmosphere and said passage.

5. In a flotation machine, the combination of an aeration chamber, a rotatable drum therein whose interior is open to the 25 atmosphere, and a casing spaced from and partially encircling said drum forming a partially cylindrical passage or aeration space, said drum having perforations establishing communication between its interior 30 and said aeration space.

In witness that we claim the foregoing we have hereunto subscribed our names this 12th day of October, 1916.

FREDERICK B. KOLLBERG.
MAX KRAUT.
